GEORGE A. PAFF, OF PORTSMOUTH, OHIO, ASSIGNOR TO WHEELING STEEL CORPORATION, OF WHEELING, WEST VIRGINIA, A CORPORATION OF DELAWARE.

MACHINE FOR TWISTING THE EYES OF WIRE REELS.

Application filed September 24, 1926. Serial No. 137,478.

This invention relates broadly to wire twisting devices, and more specifically to a machine for forming a twisted eye in wire reels of the type employed as spools for carrying in coil form lengths of fence wire and the like.

The primary object of the invention is to provide a mechanical device by means of which the eye-forming overlapping portions 10 or members of wire reels or spools may be relatively rotated to form therein eye defining twists which serve rigidly to maintain said members against relative eye-distorting movement.

15 In describing the invention in detail, reference is herein had to the accompanying drawings, forming a part of this specification, in which—

Figure 1 is a side elevation of the invention;

Figure 2 is a front elevation of the same;

Figure 3 is an enlarged sectional elevation of the jaws of the machine;

20 Figure 4 is a section on line 4—4, Fig. 3, with the jaws in their closed relation; and—

Figure 5 is an end elevation of a wire reel embodying an eye of the character produced by means of the invention.

Referring to said drawings, 1 indicates an 25 upright support of pedestal form which has rigidly mounted on the face thereof, as by means of bolts 2, a bracket embodying two supporting arms 3 and 4. The lower arm 4 has rigidly mounted thereon, as by bolts 5, 30 a stationary jaw which comprises a pair of parallel horizontally disposed side plates 6 and 7 which have in their confronting faces semi-circular channels or ways 8 in which are received laterally disposed semi-circular 35 webs 9 formed on the opposite faces of a semi-circular gear segment 10.

Pivottally mounted on the supporting arm 45 3 is the inner end of an upper jaw which comprises a pair of parallel side plates 11 and 12 which have in their confronting faces semi-circular channels or ways 13 in which are received webs 14 formed on the opposite faces of a gear segment 15 designed to complement the aforesaid gear segment 10.

50 In the lowered position of the upper jaw the latter rests upon the lower jaw in a position in which said gear segments 10 and 15 occupy closely seated complementary relation so that rotary movement imparted to one thereof is communicated to the other, said seg-

ments rotating together in the manner of a gear of ordinary unitary structure. Obviously, in such seated position of the upper jaw the ends of the ways 13 thereof accurately meet in ways 8 of the lower jaw to 60 form continuous circular bearing channels in which the webs 9 and 14 may freely rotate.

When the upper jaw becomes seated, a hook 16 fixed upon the outer end thereof is 65 automatically interlocked with a latch 17 which is pivoted intermediate its ends upon the lower jaw, whereby said jaws are positively maintained in fixed, or rigid, relation until manually disengaged by swinging said 70 latch 17 away from said hook 16. As herein shown, the latch is so formed and mounted that the force of gravity acting thereon serves normally to maintain the latch advanced to the limit of its forward movement 75 permitted by a pin 18, in which position the latch is adapted automatically to be engaged with the hook 16 when the upper jaw is lowered. Beveled faces are provided on said hook and latch for facilitating the inter- 80 engagement thereof in an obvious manner.

A pinion 19 is at all times disposed in mesh with one or the other of the gear segments 10 and 15, the same being located between the side plates 6 and 7 and being carried by a 85 shaft 20 which is journaled in the latter. Said shaft may be rotated by any suitable means, as by means of a hand crank 21 carried on an end thereof.

The upper jaw is normally maintained in 90 its elevated position by counterweights 22 and 23, the former being carried by the rear ends of parallel levers 24 which are pivoted intermediate their ends upon the upper end of the pedestal 1. Links 25 connect the front 95 ends of said levers 24 to a crosshead 26 in which is mounted the upper end of a plunger 27. Said plunger is vertically movable in a guideway 28 provided therefor in a bracket 29 carried by the pedestal 1 in an appropriate position, and has formed on its lower end an eye-piece 30 provided with an eye 31 of horizontally elongated or slot-like form. A bolt 32 mounted in brackets 33 carried by the side plates 11 and 12 of the 100 upper jaw is directed through the eye 31. Thus, the counterweight acts through the levers 24, links 25, crosshead 26, plunger 27 and bolt 32 for assisting in the support of the upper jaw in its elevated position. 110

The counterweight 23 is carried on the rear ends of parallel levers 34 which are pivoted intermediate their ends on the lower part of the pedestal 1 and which carry 5 a treadle 35 on their front ends. Links 36 have their lower ends pivoted to said levers 34 at suitable points and have their upper ends mounted on trunnions 37 borne by the crosshead 26, as shown. It will thus be 10 seen that the counterweight 23 supplements the counterweight 22 in normally maintaining the upper jaw elevated.

The gear segment 10 has formed in the middle portion of its straight edge a shallow cross recess 38, and in the middle portion of said recess is a socket 38 in which is seated an approximately cylindrical eye-sizing member 40, the latter being secured in place by a bolt 41. Each of the side plates 20 6 and 7 has therein a shallow cross channel 42. Similar cross channels 43 are also provided in the side plates 11 and 12 of the upper jaw, the same being designed, when the upper jaw is lowered, to complement the 25 channels 42 of the lower jaw in the formation of openings through which the crossing portions of a wire reel R located at opposite sides of the eye thereof may extend, while the overlapping arcuately curved eye-forming members *a*, occupying the positions shown in dotted lines in Fig. 5, lie in the recess 38 of the lower jaw in encircling relation to the member 40. The gear segment 15 is also recessed, as shown at 38^a, to correspond substantially with the recess 38 of the segment 10.

In practice, the reel R is placed in a position on the lower jaw in which the eye-forming members *a* is disposed as above described, whereupon the upper jaw is depressed to its seated position on said lower jaw and is interlocked with the latter through the intermediacy of the latch 17 and hook 16, as hereinbefore described. 40 45 Then, by rotation of the hand crank 21, the pinion 19 is actuated to rotate the complementary gear segments 10 and 15 for effecting turning of the overlapping eye-members *a*, whereby twists *b* are formed in the contacting portions of said members, as shown in Fig. 5. As is apparent, in forming said twists *b*, by one or more turns of the crank, the eye is reduced from the diameter shown in dotted lines to that shown in full lines 50 55 in said figure, the interior diameter being substantially equal to the exterior diameter of the eye-sizing member 40 embraced by the eye forming members *a*.

Following the twisting of the eye-forming 60 members, the latch 17 is disengaged from the hook 16 by downwardly directed pressure applied by hand to a handle 44 carried by the latch.

What is claimed is—

65 1. In a machine for twisting the eyes of

wire reels, a pair of relatively movable jaws adapted for receiving therebetween an eye portion of a reel, a pair of complementary gear segments carried by and rotatable in said jaws, and a pinion rotatably mounted 70 on one of said jaws and operable for rotating said segments.

2. In a machine for twisting the eyes of wire reels, a pair of relatively movable members, a segmental gear carried by said members and rotatable with respect thereto, the gear segments being adapted for receiving the eye portion of a reel therebetween a pinion carried by one of said members, and means for rotating said pinion for effecting 80 driving of said gear.

3. In a machine for twisting the eyes of wire reels, a support, a stationary member carried by said support, a member movable to and from seated relation to the stationary member, a pair of complementary semi-circular gear segments carried by said members and rotatable thereon when occupying complementary relation, said segments being designed to receive therebetween the eye portion of a wire reel, and means for rotating 90 said gear segments.

4. In a machine for twisting the eyes of wire reels, a support, a stationary member carried by said support, a member movable to and from seated relation to the stationary member, a pair of complementary semi-circular gear segments carried by said members and rotatable thereon when occupying complementary relation, said members and said gear segments having interengaging supporting and guiding means, and said segments being adapted to engage therebetween the eye portion of a wire reel, and means for 100 rotating said segments.

5. In a machine for twisting the eyes of wire reels, a support, a stationary member carried by said support, a member movable to and from seated relation to the stationary member, each of said members having 110 therein a semi-circular channel, said channels forming a circular path when said movable member occupies its said seated position, a pair of complementary gear segments having laterally projecting portions disposed for travel in said channels, and means for rotating said segments, said segments having their interengaging edge portions recessed for the reception of the eye portion of 115 a wire reel.

6. In a machine for twisting the eyes of wire reels, a support, a stationary member carried by said support, a member movable to and from seated relation to the stationary member, means normally maintaining said movable member elevated with respect to said stationary member, means for moving said movable member to seated position with respect to said stationary member, said members having therein complementary por- 125 130

tions of a circular channel, a pair of semi-circular gear segments having portions disposed for travel in said channel, said segments having recesses in their interengaging edges, and means for rotating said segments.

7. In a machine for twisting the eyes of wire reels, a support, a stationary member carried by said support, a member movable to and from seated relation to the stationary member, means normally maintaining said movable member elevated with respect to said stationary member, means for moving said movable member to seated position with

respect to said stationary member, said members having therein complementary portions of a circular channel, a pair of semi-circular gear segments having portions disposed for travel in said channel, said segments having in their interengaging portions recesses for the reception of an eye portion of a wire reel, an eye sizing member disposed in the recess of one of said segments, and means for rotating said segments.

In testimony whereof, I affix my signature.

GEORGE A. PAFF.
